US00D846381S

(12) United States Design Patent (10) Patent No.: US D846,381 S
(45) Date of Patent: * Apr. 23, 2019

(54) PACKAGING

(71) Applicant: AKRAPOVI# D.D., Ivancna Gorica (SI)

(72) Inventors: Slavojka Akrapovic, Ljubljana (SI); Andrej Percic, Kranj (SI)

() Term: 15 Years

(21) Appl. No.: 35/504,440

(22) Filed: Jan. 25, 2018

(80) Hague Agreement Data

Int. Filing Date: Jan. 25, 2018

Int. Reg. No.: DM/099567

Int. Reg. Date: Jan. 25, 2018

Int. Reg. Pub. Date: Feb. 16, 2018

(30) Foreign Application Priority Data

Aug. 3, 2017 (EM) 004132892-0001
